UNITED STATES PATENT OFFICE.

JOSEPH S. ALDERMAN, OF ENNIS, TEXAS.

BURGLAR-ALARM.

1,244,938.

Specification of Letters Patent. Patented Oct. 30, 1917.

Application filed March 8, 1916. Serial No. 82,875.

To all whom it may concern:

Be it known that I, JOSEPH S. ALDERMAN, a citizen of the United States, residing at Ennis, in the county of Ellis and State of Texas, have invented certain new and useful Improvements in Burglar-Alarms; and I do hereby declare the following to be a full, clear, and exact description of the invention, such as will enable others skilled in the art to which it appertains to make and use the same.

This invention relates to burglar alarms, and has for its primary object to provide a simple and efficient device of this character adapted to be automatically released by the opening movement of a window or door to sound an alarm and thus give warning.

With this and other objects in view, the invention consists in the novel construction, combination and arrangement of parts as will be hereinafter specifically described, claimed and illustrated in the accompanying drawings, in which:

Figure 1 represents a front elevation of a door, illustrating the improved burglar alarm applied to use thereon,

Fig. 2 represents a longitudinal sectional view on the line 2—2 of Fig. 1,

Fig. 3 represents a horizontal sectional view on the line 3—3 of Fig. 1,

Fig. 4 represents a front elevation of the burglar alarm applied to a window,

Fig. 5 represents a vertical sectional view on the line 5—5 of Fig. 4, and

Fig. 6 is a perspective view of the firing member.

Referring to the drawing in detail, wherein similar reference numerals designate corresponding parts throughout the several views, the numeral 8 indicates an elongated body member having a relatively wide longitudinal slot 9 adjacent one end thereof connected with a transverse opening 10 formed adjacent the opposite end by a centrally located connecting bore 11. Adjacent the opposite ends the body or base 8 is formed with apertures 12 disposed in parallel relation to the opening 10 and adapted to receive screws, or equivalent means, whereby the base is secured in position to a door or window frame. A cartridge holder 13 is secured in the bore 11 in the end adjacent the slot 9.

A firing element 14 is slidably mounted in the relatively wide slot 9 and is provided with a transverse guide pin 15 slidably re-

ceived within slots 16 formed in the side walls of the slot 9 and disposed at right angles to the latter. The firing member 14 is provided with reduced lateral extensions 17 projecting outwardly of the base 8 and having apertures 18 therein receiving the upper extremities of operating springs 19, the lower ends of which are mounted in apertured ears 20 formed adjacent the lower end of the base 8. A U-shaped strap 21 is connected with the upper portion of the slideable firing member 14 and receives one end of a lever 22, having a longitudinal slot 22a pivotally receiving a pin 23 fastened to a window, door or other suitable supporting frame and adapted to coact with devices carried by the door or window to retain the firing member 14 in elevated or inoperative position, while the door or window is in closed position. When the alarm is not in use, the lever 22 drops by gravity into the vertical position illustrated in dotted lines in Fig. 1 and is thus rendered inoperative.

In applying the burglar alarm to use in connection with a swinging door, the base 8 is secured in position upon the door frame 24 by screws fitted in the apertures 12 and secured in the door frame. The lever 22 is pivotally secured to the door frame 24 by the screw, or equivalent means, 23 at a point adjacent the upper extremity of the slot 9 in the base, the outer end of the lever being extended through the slot 9 and the strap 21 carried by the firing element 14. A plate 25 is rigidly secured adjacent the vertical swinging edge of the door 26 and the outer end 27 thereof is twisted and so arranged that when the door is closed the twisted end 27 is disposed above the adjacent end of the lever 22 and operates to retain the firing element in elevated or inoperative position against the tension of the operating springs 19. When the door is opened, the twisted end 27 of the plate is moved off of the adjacent end of the lever 22, thus releasing the latter and permitting the firing element 14 to move downwardly in the base 8 under the influence of the springs 19, thus forcibly engaging the firing pin 28 carried by the member 14 into engagement with the blank cartridge 29, exploding the latter and giving an alarm.

In applying the alarm to a window, the base 8 is attached to the window frame 30 and the lever 22 is controlled by angular plates 31 fastened to the lower sash 32.

What I claim is:

1. A burglar alarm including a base having a relatively wide longitudinal slot, a bore communicating with the lower end of the slot, and a transverse opening therethrough communicating with the lower end of the bore and constituting an outlet for the latter, a firing element slidably mounted in the relatively wide slot and projecting laterally of the base, the walls of the slot having relatively narrow slots therein, a guide pin projecting laterally of the opposed sides of the firing element and slidably received in the relatively narrow slots, a firing pin carried by the firing element, a cartridge holder in the upper end of the bore, springs arranged on opposite sides of the base and connecting the opposite ends of the firing element with the lower terminal of the base and normally tending to move said firing element to operative position, and a pivoted lever associated with said firing element for releasably retaining the latter in inoperative position.
2. A burglar alarm including a base having a relatively wide longitudinal slot, a bore communicating with the lower end of the

slot, and a transverse opening therethrough communicating with the lower end of the bore and constituting an outlet therefor, a firing element slidably mounted in the relatively wide slot and projecting laterally of the base, the walls of the relatively wide slot being provided with relatively narrow slots therein, a guide pin carried by the firing element slidably received within the relatively narrow slots, a firing pin carried by the firing element, a cartridge holder in the upper end of the bore, springs connecting the exposed portions of the firing element with the lower portion of the base and normally tending to move the firing element to operative position, a U-shaped strap connected with the firing element, and a pivoted lever associated with the strap for releasably supporting the firing element in inoperative position.

In testimony whereof I affix my signature in presence of two witnesses.

JOSEPH S. ALDERMAN
